UNITED STATES PATENT OFFICE

HOMER J. HAMILTON AND AUVRY E. STONE, OF SOUTH BEND, INDIANA

DESIGN FOR A BOOK END

Application filed April 10, 1931. Serial No. 39,434. Term of patent 3½ years.

To all whom it may concern:

Be it known that we, HOMER J. HAMILTON and AUVRY E. STONE, citizens of the United States, residing at South Bend, in the county of St. Joseph and State of Indiana, have invented a new, original, and ornamental Design for Book Ends, of which the following is a specification, reference being had to the accompanying drawings, forming part thereof.

I claim:

The ornamental design for a book end, as shown.

HOMER J. HAMILTON.
AUVRY E. STONE.
